US0D1057133S

(12) **United States Design Patent** (10) **Patent No.:** **US D1,057,133 S**
(45) **Date of Patent:** **** Jan. 7, 2025**

(54) **PET WATER DISPENSER CARTRIDGE**

(71) Applicant: **Changjiang Fu**, Heyuan (CN)

(72) Inventor: **Changjiang Fu**, Heyuan (CN)

(**) Term: **15 Years**

(21) Appl. No.: **29/945,477**

(22) Filed: **Jun. 3, 2024**

(51) LOC (15) Cl. **23-01**

(52) U.S. Cl.

USPC **D23/209**
